UNITED STATES PATENT OFFICE

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA

SECTIONAL FORMER

Application filed August 18, 1927, Serial No. 213,848. Renewed June 20, 1929.

This invention relates to the formers of newspaper printing presses. The principal objects of the invention are to provide a simple and convenient way of arranging for the support of the paper between the formers when they have to be separated to take a wider web; to provide a means connected with each former and carried thereby which can be moved into and out of position, according to the adjustment of the formers for taking a wide or narrow web, which will provide a bearing means all the way across the web, and to provide improvements in the details of construction of the same.

Reference is to be had to the accompanying drawings in which

Fig. 1 is a front view of a former shown as applied to a folder constructed in accordance with this invention and in position for receiving wide webs;

Fig. 2 is a similar view showing the same former in position for receiving narrow webs;

Fig. 3 is a fragmentary view similar to Fig. 1 on enlarged scale;

Fig. 4 is a plan of the same;

Fig. 5 is a sectional view on the line 5—5 of Fig. 4;

Fig. 6 is a view similar to Fig. 2 on enlarged scale, and

Fig. 7 is a plan thereof.

As is well understood in this industry, newspaper printing presses are equipped ordinarily with two formers over the folder placed side by side so that their noses are in line with the intermediate margins of a four page wide web. When the width of the web is changed, the formers are moved farther apart or brought closer together in accordance with the width of the web. When moved farther apart, a space is left between the formers so that the web is unsupported throughout that space during its passage over the former. This invention is designed to provide for filling that space without having any parts that have to be attached and removed, thereby causing difficulty.

For this purpose I provide on the inner edge of each former 10 a removable section 11 which is hinged to the former by any de-

sired means as for example a longitudinal hinge pin 12. The removable section 11 is adapted to be swung on this pin from the position shown in Fig. 4, where a wide web is accommodated, to the position shown in Fig. 7 to accommodate a narrow web. The combined width of two of these removable portions 11 is equal to the space that is left when the formers are moved apart ordinarily. The former and the removable section are of the same thickness and the latter rests back on the rear surface of the former when not in use as shown in Figs. 6 and 7.

For the purpose of holding them in place, pins 13 are provided for receiving the rear sides of the removable section when they are folded back. These pins 13 are located near the rear of each former and are provided with heads. Corresponding headed pins 17 are provided at the same distance from the back of each former at a distance from the pins 13. On each removable section 11 is a pin 14 having a head on which is swingingly mounted a locking arm 15. This is pivoted to swing freely and is provided with a notch 16 and a handle 18 in the form of a headed stud on the arm.

With the parts in the position shown in Fig. 4, where removable sections are inserted between the two formers and in the same plane, the locking arms are swung on their pivots 14 so that the notches 16 will receive the pins 13. This holds this section 11 with the arm 15 serving as a strut across the pivot angle. Therefore they are rigidly supported and will carry all the weight and pressure that is likely to be applied to them.

When it is desired to use the formers for a narrower width web the two removable sections 11 are swung back on their pivots 12 to the position shown in Figs. 6 and 7, the arms 15 first having been removed from the studs 13. After these sections are brought back against the rear of the two formers the two arms 15 are swung outwardly on their pivots 14 so that the notches 16 will receive the pins 17, as shown in Fig. 7. This holds the sections 11 in stationary position until the arms 15 are moved away from the pins 17.

It will be seen therefore that each remov-

100

able section may be quickly swung out of the way to the position shown in Figs. 6 and 7 when it is desired to bring the two formers together to receive a narrow web. On the other hand, when a wide web is to be run, the removable sections are swung back into line with the former so that the web will be supported through its entire width at all times. The sections 11 are rigidly supported in both

10 positions.

Although I have illustrated and described only a single form of the invention, I am aware of the fact that modifications can be made therein by any person skilled in the art 15 without departing from the scope of the invention as expressed in the claims. Therefore, I do not wish to be limited to all the details of construction herein shown and described, but what I do claim is:

20 1. The combination with two formers arranged side by side and movable apart, of two sections adapted to be located between them when they are moved apart to form continuations of the formers and support 25 the web between them, and to be swung back beneath the formers to permit the formers to be moved nearer together.

2. The combination with a pair of formers, of a section pivotally mounted on each former 30 on their adjacent edges and adapted to be swung back to the rear of and beneath the formers to permit the formers to be moved nearer together.

3. A former for a folding machine having 35 a section removably connected with its edge and adapted to be moved out of the plane of the operative surface of the former and to be restored thereto for the purpose of filling the space between two formers 40 when a narrow width web is run.

4. The combination with a former, of a removable section constituting a part of the former and having a surface normally flush with the surface of the former mounted to 45 swing on an axis parallel to the side of the former around back out of the way and a locking arm pivoted on the removal section and adapted to be connected with the former to hold the pivotal section in either of its 50 extreme positions.

5. As an article of manufacture, a former for a folding machine having converging edges and provided with a detachable section near the base of one of said edges and having 55 its edge constituting a continuation thereof, and a longitudinal hinge connecting said section with the former, said hinge being arranged along the edge of the former at the rear thereof, whereby said detachable section can be swung from a position in the same plane as the former to a position in which it is folded against the rear of the former.

6. The combination with two formers arranged side by side and movable apart, of 60 two parallel sections adapted to be located

between them when they are moved apart to form continuations of the formers and support the web between them.

7. The combination with a pair of formers arranged side by side, of a removable and 70 replaceable section located adjacent to the edge of one former and between the two formers for widening that former.

In testimony whereof I have hereunto affixed my signature.

HENRY A. WISE WOOD.
